UNITED STATES PATENT OFFICE.

HERMAN L. PETERS, OF BUFFALO, NEW YORK.

SPRING-LOCK.

1,299,859.

Specification of Letters Patent.

Patented Apr. 8, 1919.

Application filed September 3, 1918. Serial No. 252,290.

To all whom it may concern:

Be it known that I, HERMAN L. PETERS, a citizen of the United States, residing at Buffalo, in the county of Erie and State of New York, have invented new and useful Improvements in Spring-Locks, of which the following is a specification.

This invention relates to the class of spring locks having safety means for dead-locking the bolt in its projected position to defeat attempts to pick the lock, for example by the pressure of a hooked wire or similar implement against the beveled end of the bolt. The lock is especially desirable for the doors of street and house mail-boxes, but it is also applicable to the doors of various other articles, as well as the drawers of cabinets, desks and other furniture.

The object of my invention is the improvement of the dead-locking device with a view of simplifying its construction, reducing its cost and rendering it positive and reliable in action.

In the accompanying drawings:

Figure 1 is a front view of the lock applied to a mail box, a part of the case being broken away and the bolt being shown dead-locked. Fig. 2 is a similar view showing the position of the tumblers when the bolt is retracted by a proper key. Fig. 3 is a similar view showing the position of the tumblers after the bolt has been retracted by the key and allowed to spring to its projected position. Fig. 4 is a perspective view of the bolt. Fig. 5 is a similar view of the auxiliary tumbler. Fig. 6 is a horizontal section on line 6—6, Fig. 3.

Similar characters of reference indicate corresponding parts throughout the several views.

1 indicates the door of a mail-box to which the improved lock is applied, and 2 the usual striker-plate secured to the jamb.

3 indicates the body of the lock-case and 4 its face-plate having the customary opening for the passage of the beveled spring-bolt 5. The latter has the usual key-notch 6 and is projected by a spring 7 of any ordinary construction. The bolt is guided by 50 the customary pin 8 secured to the case and passing through a longitudinal slot 9 of the bolt. The bolt is also provided with a locking stud or lug 5^a. The lock has a suitable number of main tumblers 10 which are all pivoted at their inner ends upon the pin 8. Each of them is provided in its free end

with a gate 12 for the bolt-stud 5^a having at its inner end a lateral enlargement 13. Each tumbler also has the usual stop lug 14 for limiting its forward swing under the action 60 of its spring 15. These main tumblers, while free to swing on the pivot 8, are incapable of sliding lengthwise thereon.

16 indicates an auxiliary tumbler which preferably lies between the bolt and the adjacent main tumbler 10, but unlike the latter, is free to slide longitudinally on the pivot-pin 8 as well as swing thereon, being slotted at 17 for this purpose. It has a spring 18, similar to the springs of the main tumblers; a gate 19 and a stop-lug 20 at its free end and a key-notch 21 in its front edge adapted to receive the key-bit 21^a. The auxiliary tumbler also carries a blocking-stud 22 arranged to enter the enlargements 13 of 75 the several main tumblers in the depressed position of the auxiliary tumbler, as shown in Fig. 1, and to occupy the gates of the main tumblers and block their forward movement in the advanced position of the 80 auxiliary tumbler, as shown in Fig. 3. The stud of the auxiliary tumbler is of the proper length to engage all of the various tumblers and it is arranged to be encountered by the bolt stud 5^a when the bolt is unlocked and 85 withdrawn by the key.

The operation of the lock is as follows:

In the position of the parts shown in Fig. 1, the bolt is dead locked by the ends or shoulders of the main and auxiliary tumblers engaging behind the bolt-stud 5^a. The auxiliary tumbler is in its depressed or retracted position and its blocking-stud 22 occupies the gate-enlargements 13 of the main tumblers, allowing the latter to swing to the 90 limit of their forward movement and lock the bolt.

Upon inserting the key and turning it forwardly to unlock the bolt, the main tumblers are first swung backwardly by the key-bit, 100 bringing the narrow portions of their gates 12 in register with the bolt-stud 5^a. By the same movement of the key, the auxiliary tumbler 16 is swung backwardly to move its free end clear of the bolt-stud. By the continued rotation of the key, the bolt is fully retracted as usual, to unlock the door. During this movement of the bolt its stud 5^a engages the stud 22 of the auxiliary tumbler and slides the latter inwardly on the pivot 110 pin 8 to the position shown in Fig. 2. Upon now turning the key backwardly far enough

to release and withdraw it, the bolt is projected by its spring 7 in the usual manner, and the auxiliary tumbler is shifted outwardly to its former position by the engagement of the 5 key bit with its notch 21, bringing its stud 22 into the narrow portion of the main-tumbler gates 12, as shown in Fig. 3, thereby blocking the forward swing of said tumblers and preventing them from engaging behind 10 the bolt stud and locking the bolt. By the same movement, the outer end or shoulder of the auxiliary tumbler is carried beyond the inner edge of the bolt-stud 5^a and said shoulder cannot therefore engage behind said stud 15 and lock the bolt. The latter is thus free to slide inwardly. Upon again closing the door to automatically lock it, the bolt is pressed inwardly by engaging the striker-plate 2 and the auxiliary tumbler is shifted inwardly to 20 the position shown in Fig. 2 by the stud 5^a striking the stud 22, as above described. However, as there is now no key in the lock, the auxiliary tumbler is not again advanced, but remains in its inner position in which its 25 stud occupies or stands opposite the enlargements 13 of the main tumbler gates, as shown in Fig. 1, permitting free forward movement of the main tumblers. It follows that the moment the bolt is again projected by its 30 spring 7 to lock the closed door, its stud 5^a is withdrawn from the gates of the main tumblers, allowing the free ends of the latter to swing behind the bolt stud and dead-locking the bolt. Simultaneously with this 35 action, the free end of the depressed auxiliary tumbler engages behind the bolt-stud and aids in locking the bolt.

While effectually baffling attempts to pick the lock, this improvement accomplishes the 40 desired result by exceedingly simple and inexpensive means, the only part added to the ordinary parts of such a spring lock being the auxiliary tumbler.

While I have herein shown the improvement as embodied in a lock in which the tumblers are operated directly by a key, the invention is obviously applicable to locks of the type in which they are indirectly operated by a knob or a key through one or more 50 intermediate elements.

I claim as my invention:

1. In a lock of the character described, the combination of a bolt, a main tumbler, and an auxiliary tumbler shiftable lengthwise of 55 the main tumbler and carrying means for engaging and holding the main tumbler in its inoperative position after it has been manually moved aside and the bolt has been retracted and released.

60 2. In a lock of the character described, the combination of a bolt, a swinging main tumbler incapable of longitudinal movement on

its pivot, and an auxiliary tumbler capable of a compound swinging and longitudinal movement and having means for holding the 65 main tumbler in its inoperative position after it has been swung aside by a key and the bolt has been retracted and released by the key.

3. In a lock of the character described, the combination of a bolt having a locking-stud, 70 a main tumbler having a gate for said stud provided with a lateral enlargement, and an auxiliary tumbler movable both laterally and lengthwise of said main tumbler and having a stud arranged to occupy the narrow portion of said main-tumbler gate in one position of the auxiliary tumbler and to occupy the enlargement of said gate in another position of the auxiliary tumbler.

4. In a lock of the character described, the 80 combination of a bolt having a locking-stud, a main tumbler having a gate for said stud provided with a lateral enlargement, and an auxiliary tumbler movable both laterally and lengthwise of said main tumbler, said auxiliary tumbler having a shifting-notch adapted 85 to receive a key-bit and a stud arranged to occupy the narrow portion of said main-tumbler gate in one position of the auxiliary tumbler and to occupy the enlargement of 90 said gate in another position of the auxiliary tumbler.

5. In a lock of the character described, the combination of a bolt having a locking stud, 95 a main tumbler having a gate for said stud provided with a lateral enlargement, a tumbler-pivot, and an auxiliary tumbler having a longitudinal slot engaging said pivot to permit a compound swinging and longitudinal movement of the auxiliary tumbler 100 relative to said main tumbler, said auxiliary tumbler having a shifting-notch for a key-bit and a stud adapted to be engaged by said bolt-stud and arranged to occupy the narrow portion of said main tumbler-gate when the 105 auxiliary tumbler is shifted toward the front end of the bolt and to occupy the enlargement of said gate when the auxiliary tumbler is shifted in the opposite direction.

6. In a lock of the character described, the combination of a bolt having a locking-stud, 110 a main tumbler having a gate for said stud provided with a lateral enlargement, and an auxiliary tumbler movable both laterally and lengthwise of said main tumbler and having 115 a gate for the bolt-stud and a stud arranged to occupy the narrow portion of said main tumbler-gate when the auxiliary tumbler is shifted toward the front end of the bolt and to occupy the enlargement of said gate when the auxiliary tumbler is shifted in the opposite direction.

HERMAN L. PETERS.
